UNITED STATES PATENT OFFICE

JOSEPH VAN ACKEREN, OF PITTSBURGH, PENNSYLVANIA, ASSIGNOR TO THE KOPPERS COMPANY OF DELAWARE, A CORPORATION OF DELAWARE

VERTICAL COKING RETORT OVEN

Application filed April 12, 1927. Serial No. 183,085.

My invention relates to coking retort ovens of the vertical type and it has particular relation to means for supporting the battery structure and for controlling the temperatures of the supporting means and the adjacent battery structure.

My invention has for one of its objects to provide a structure whereby the base portion of a coke oven battery of the vertical type is provided with cooling means to reduce the temperature and thereby the expansion of the lower portion of the battery.

A further object of my invention is to provide a vertical coke oven battery that is so constructed and arranged that the foundations thereof are not subjected to any material forces tending to spread them when the battery is heated to operating temperatures.

A further object of my invention is to provide supporting means having heat-insulating means embodied therein to prevent excessive temperatures of the supporting means.

A further object of my invention is to provide simple and effective means for supporting the base of a vertical coke oven battery and which will readily permit the passage of columns of coke therethrough.

A still further object of my invention is to provide means whereby the base of a vertical coke oven battery is effectually sealed in such manner that there is no exposed brickwork and no leakage of gas through the joints in the brickwork.

In the construction and operation of vertical coke ovens as practiced heretofore, the oven structures have been supported by metal beams secured to the concrete foundation. The foundation has been subjected to severe strains because of the relatively great expansion of the beams when the latter were highly heated. In addition, gas leaked through the joints in the base of the oven structure and burned beneath the battery with the result that the beams were warped by the unequal heating.

When the structure referred to above has been employed, it has been necessary to support the coke extractor mechanism from the beams and an intermediate structure has

been required to connect the extractors to the beams.

In accordance with the present invention, I provide means whereby much lower temperatures are maintained in the base portion and in the supporting structure by providing air-cooling means for the supporting structure and part of the base portion of the battery and, in addition, by providing heat-insulating means for a portion of the structure in contact with the hot coke. Expansion of the supporting structure is thereby limited.

The beams of the former constructions have been replaced by supporting frames which completely cover the brickwork of the base and are sealed at adjacent edges to prevent leakage of gas. The frames and coke extractors are directly connected and any intermediate structure is eliminated and, to that extent, the height of the structure is diminished.

In the accompanying drawings,

Figure 1 is a view, partially in end elevation and partially in section, of a vertical coke oven battery constructed in accordance with my invention;

Fig. 2 is an enlarged view, partially in end elevation and partially in section, along the line II-II of Fig. 3, of a portion of the vertical coke oven battery of Fig. 1, parts being broken away;

Fig. 3 is a view, partially in side elevation and partially in section along the line III-III of Fig. 2, of a portion of the coke oven battery.

A vertical coke oven battery 1 comprises a foundation 2, which may be of concrete or other suitable material, that is supported upon columns 3. The oven structure 4, which rests upon the foundation 2, is provided with a superstructure 5. A charging car 6 supplies coal magazines 7 at the tops of the several retort ovens of the battery. A primary gas offtake 8 is located at the top of each retort oven and is connected to a primary collecting main 9. A secondary gas offtake 10 for each oven is connected to a secondary collecting main 11.

As shown in Figs. 2 and 3, the battery 1

comprises a plurality of vertical retort ovens 12 that alternate with heating walls 13. The battery may comprise any suitable number of ovens, for example, five, but only two 5 ovens are shown herein, the remainder being identical with those shown and described. The battery is provided with the usual side walls 14 and 15 and regenerators 16, only a portion of one of the latter appearing in 10 Fig. 2. The oven structure 4 is supported upon the foundation 2 which comprises horizontal concrete beams 17 and 18, only portions of which appear in Figs. 2 and 3, the remainder being broken away for the sake 15 of clearness. The beams 17 and 18 extend under the outside walls of the battery and are supported upon the columns 3.

The portions of the oven structure between the beams 17 and 18 are supported by castings or frames 19, each having a central opening which conforms to the bottom opening of the corresponding oven. As best shown in Fig. 3, each of the frames 19 of adjacent ovens supports substantially one-half of the intermediate heating wall. As 20 shown in Fig. 2, the end portions of the frames 19 project into the beams 17 and 18 and are supported thereby. Each frame 19 is provided with tie rods 20 on the sides 25 thereof and extending between the beams 17 and 18.

An expansion joint 22, consisting of pitch between the end of each frame 19 and the beam 18 provides for the expansion of the 30 frame 19 under ordinary operating conditions without subjecting the foundations to injurious strains. An expansion joint 23 is also provided between the adjacent side edges 35 of the frames 19 for maintaining a gas-tight 40 connection between them. The expansion joint 23 comprises an inner body of pitch that is retained by asbestos rope indicated at 24 which occupies a groove formed by adjacent recessed flange portions 25 of the 45 frames 19.

Each of the frames 19 is provided, at its upper portion, with a hollow flange 27, substantially rectangular in cross-section, and that extends around the periphery of the 50 frame. The flange 27 is provided with suitably spaced vertical reinforcing webs or walls 28, which divide the flange into compartments the dividing walls 28 being provided with circular openings 29 in order to provide 55 communication between the several compartments. The bottom walls of the side compartments are provided with comparatively large openings 30, which communicate with the atmosphere.

60 Certain of the compartments at the end of the frame 19 are open to the atmosphere through vertical passageways 32. The end portions of the casting are each provided with horizontal flanges 33 and 34 that are 65 in extension of the upper and the lower

sides of the flange 27 and also with a flange 35, the several end flanges extending into the beams 17 and 18. The spaces between the flange portions 33 and 34 communicate with the hollow flange 27.

Immediately below the regenerators 16 are two air ducts 36 that are connected at their outer ends to the atmosphere and at their inner ends communicate with the space between the flanges 33 and 34 at the right end 70 of the frame 19, as viewed in Fig. 2. The left end of the frame 19 is also connected to two air ducts 37 that communicate with the atmosphere. Accordingly, the openings 30, the passages 32, the hollow flange 27 with 75 the openings 29 and the spaces between the flanges 33 and 34 with the connected air ducts 36 and 27 constitute means for circulating air through and around the frame 19 to cool the latter. It will be understood that each 80 of the frames 19 is connected to similar ducts 36 and 37.

The frame 19 is further provided with an upper inwardly extending upper flange 39 and a similar lower flange 40 that conform 90 to the opening of the oven 12. The space between the flanges 39 and 40 is filled with refractory material 41, such, for example, as firebrick, to constitute in effect an extension of the bottom opening of the oven 12. 95 The refractory material 41 also constitutes a heat-insulating envelope that surrounds the column of coke for a distance of a few feet below the bottom of the oven.

Beneath the frame 19 and secured for support thereto is a casing 42 of somewhat irregular contour that is inclined to the right, as viewed in Fig. 3, the left-hand side of the casing 42 constituting a partial support for the column of coke. A coke extractor comprises a shaft 43 extending through the casing 42 and upon which is mounted a series of toothed wheels 44 for the purpose of removing coke from the base of the column. A series of pivotally mounted weight members 45 have their movable ends adjacent to corresponding toothed wheels 44 and operate to yieldingly prevent coke from falling from the column other than when it is removed by the wheels 44.

Beneath the mechanism just described and supported by the casing 42 is a storage chamber or hopper 46, into which the coke falls when it leaves the casing 42. The hopper 46 is provided, at its bottom portion, with a water-sealed door 47 that is rotatably mounted at 48. Each side of the door 27 is normally immersed in a water seal 49. When the door is opened, it permits coke to flow cut a discharge opening 50.

The coke-extractor casing 42 is provided with suitable means for quenching or cooling the coke after it emerges from the frame 19, comprising a series of waterpipes 52, by means of which jets of water are applied 130

to the coke just prior to its removal from the base of the column by the coke extractor. It is very desirable that the cooled coke be as dry as possible and, to this end, means are provided for preventing any excess quenching water from coming in contact with the coke in the hopper 46. The casing 42 comprises a curved portion 53 having an extending portion 54 beneath which is located a horizontal trough 55 for collecting any water that may flow down the side of the casing or drip from the coke prior to its entry into the hopper 46. The trough 55, which extends substantially the entire length of the coke extractor, directs the water to the inclined end walls of the hopper 46, by means of which it is directed into the water seal 49. The latter may be provided with any suitable means to take care of overflow.

The trough 55 is mounted for rocking movement by means of ears 56 and short shafts 57 and 58 that are rotatably supported at their respective inner ends by lugs 59 and at their outer ends by the extractor casing 42. The shaft 58, which is rotatable with the trough 55, extends through the casing 42, the outer end being provided with a loosely mounted handle 60, whereby the trough may be tilted at desired times to remove any breeze coke that may collect therein. The trough is locked in position by sliding the handle on the shaft 48 to engage a stop 61.

A water pipe 62 provides means for flushing the trough 55 at desired times to facilitate the flow of water therein.

In the operation of the battery, the ovens 12 are heated by the heating walls 13, the latter being provided with horizontal flues 64 and 65 for conveying products of combustion and with heating flues 66, only a portion of which are shown in Fig. 3. A cross-around flue 67 is shown in the wall 14, Fig. 2. The base of each heating wall is provided with an inspection opening 68. A pipe 69, having an outer movable cap 70, extends through the flange 27 of the corresponding frame 19 in registry with each opening 68 to provide access thereto.

The finished product in the form of a more or less compact column of highly heated coke emerges gradually from each oven 12 and passes downwardly through the frame 19 to engage the casing 42. The column of coke is broken as it is deflected in its downward passage toward the coke extractor. The pivoted weight members 45 prevent loose portions of the coke from falling until they have been actuated by the coke extractor. The coke extractor, which may be suitably driven by any external power means, is operated at the rate corresponding to that at which the coal is properly coked, the downward movement of the column being dependent upon the speed of the coke extractor. The coke is

quenched just prior to its reaching the coke extractor and its temperature is so reduced that no combustion occurs thereafter. The accumulated coke in the hopper 46 is dumped into cars or suitable conveyors at desired intervals for storage or shipment. 70

During the operation of the battery, the heating walls 13 and the side walls 14 and 15 reach fairly high temperatures and heat is conducted to the frames 19, including their hollow flanges 27. Since the air ducts 36 and 37 are connected to the atmosphere, a draft occurs through the hollow flanges 27 and their connected parts and heated air is thereby conducted to the atmosphere at the sides of the battery. The operation of the air-cooling system thus provided operates to dissipate heat from the frames 19 and the lower portion of the battery and thus maintains these parts at comparatively low temperature. 85

In addition, the refractory linings 41 for the frames prevent any considerable portion of the heat from the columns of coke from being transmitted through the supporting frames and the coke is quenched almost immediately after leaving the frames by the water and steam that is generated therefrom. 90

The result of the use of the supporting means having air-cooling means and the heat-insulating means incorporated therein is to materially reduce the temperatures obtaining in the supporting structure and the base of the battery and thereby diminish the expansion of the supporting structure that has heretofore attended the operation of coke oven batteries. Furthermore, the provision of expansion joints, in addition to the low temperatures of the frames, relieves the foundation from forces tending to spread them and which might cause their fracture or their failure. 100

The supporting frames with their sealed adjacent edges affords a gas-tight covering for the entire base of the brickwork and there can be no leakage of gas through the joints of the latter. The direct connection of the supporting frames and the coke extractor results in a shorter structure beneath the battery and effects a saving in total height. 110

I have provided simple and efficient means in the form of a trough for preventing excess quenching water from coming in contact with the quenched coke and the trough is so arranged that it may be moved from without the extractor to render it fully operative. 120

The foregoing and other advantages will be apparent to those skilled in the art to which my invention relates. My invention may be variously modified and it is understood that it is not to be limited except as expressed in the appended claims. 125

I claim as my invention:

1. In a vertical coke oven battery, the combination with a main oven structure, of sup- 130

- porting means therefor comprising spaced outer members and bridging members therebetween and supported thereby, and an expansion joint between each of said bridging members and one of said outer members.
5. In a vertical coke oven battery, the combination with a main oven structure comprising a plurality of ovens having openings through the base of said structure, of supporting members for said structure, each of said members having an opening conforming to that of an oven, and the side edges of said members having gas-tight expansion joints therebetween whereby the base of the oven structure is entirely covered and leakage of gas therethrough is prevented.
10. In a coke oven battery, the combination with a plurality of vertical retort ovens each comprising two adjacent side walls and an oven chamber therebetween and having a bottom opening, of supporting means for said battery comprising foundation walls along the periphery of the battery and bridging members extending between said foundation walls, said bridging members each having an opening conforming to the bottom opening of an oven chamber and having a gas-tight connection to adjacent bridging members and having also an expansion joint connection to the foundation walls.
15. In a vertical coke oven battery, the combination with a main oven structure comprising spaced foundation members, a plurality of ovens having openings through the base of said structure, of metallic supporting members for said structure supported by said foundation members and having openings conforming to the openings of said ovens and having adjacent side edges that have a gas-tight connection therebetween for providing a bottom covering for said oven structure for preventing leakage of gas therethrough.
20. In a coke oven, the combination with a vertical retort oven comprising two adjacent walls that are spaced to provide a vertical retort oven chamber therebetween and having a bottom opening, of means for supporting portions of said walls surrounding said oven chamber, said means comprising foundation walls and a metallic frame extending between said foundation walls and having an opening conforming to the bottom opening of said oven supported thereby and having hollow portions adjacent to the oven walls and communicating with the atmosphere for circulating air for cooling said frame and the adjacent portions of the oven walls and thereby restricting the spreading of said foundation walls.
25. In a coke oven, the combination with a vertical retort oven comprising two adjacent walls that are spaced to provide a vertical retort oven chamber therebetween, said chamber having a bottom opening, of means for supporting portions of said walls, said means comprising two spaced foundation walls and a metallic member extending between and directly supported by said foundation walls and having an opening conforming to the bottom opening of said oven chamber and having also a hollow portion adjacent to the oven walls and communicating with the atmosphere to provide an inlet and an outlet for air for cooling said metallic member and the adjacent portions of said oven walls.
30. In a vertical coke-oven structure, the combination with a plurality of spaced foundation walls, a retort oven having side walls for bridging the space between said foundation walls, of a metallic bridging member extending between and connected to said foundation walls for supporting portions of said side walls and having hollow portions adjacent to said side walls that are adapted to allow air to circulate therethrough to provide cooling means therefor for restricting the forces tending to spread said foundation walls.
35. In a vertical coke oven, the combination with a main oven structure comprising a retort oven having a bottom opening, of supporting means therefor comprising spaced outer members, a metallic bridging member therebetween and supported thereby, said bridging member having an opening therethrough and conforming substantially to that of said oven and having also hollow portions surrounding said bottom opening and adjacent the bottom portion of said oven structure for admitting air for cooling said bridging member and the bottom portion of said oven structure to restrict the temperatures thereof and thereby limit stresses on said outer members tending to separate them.
40. In a coke oven, the combination with a main oven structure comprising a vertical retort oven and walls therefor, said oven having a bottom opening, of side supporting members for said structure and a metallic frame member connected to said side members and extending therebetween for supporting the intermediate oven structure, said member having hollow portions for admitting air adjacent to the bottom portions of said walls for cooling said member and said bottom portions of said walls and thereby limiting the forces tending to spread the supporting members.
45. In a coke oven, the combination with a vertical retort oven comprising two adjacent walls that are spaced to provide a vertical retort oven chamber therebetween, said chamber having a bottom opening, of means for supporting portions of said walls, said means comprising a metallic member having an opening therethrough conforming to the bottom opening of said oven chamber and having also a hollow portion surrounding said opening in said member and adjacent to said

walls, said hollow portion being connected at its top and bottom to the atmosphere to constitute air-cooling means for said walls.

11. In a coke oven, the combination with a vertical retort oven comprising two adjacent walls that are spaced to provide a vertical retort oven chamber therebetween, said chamber having a bottom opening, of means for supporting portions of said walls, said means comprising a metallic member having an opening therethrough conforming to the bottom opening of said oven chamber and having also a hollow portion surrounding said opening in said member and adjacent to said walls, 15 said hollow portion being connected at its top and bottom to the atmosphere to constitute air-cooling means for said walls, and a refractory lining for said member.

In testimony whereof, I have hereunto subscribed my name this 9th day of April, 1927.

JOSEPH VAN ACKEREN.
